United States Patent Office

Des. 192,165

Patented Feb. 6, 1962

192,165

VEHICLE SEAT

Joseph J. Brandon, Highland Park, Ill., assignor to Coach & Car Equipment Corporation, Chicago, Ill., a corporation of Illinois

Filed Apr. 3, 1961, Ser. No. 64,574

Term of patent 3½ years

(Cl. D15—8)

Fig. 3.

Fig. 1.

Fig. 4

Fig. 2

FIGURE 1 is a front elevational view of a vehicle seat showing my design;

FIGURE 2 is a top view;

FIGURE 3 is a side elevational view taken from the left of FIG. 1, and

FIGURE 4 is a rear elevational view thereof.

The side of the seat now shown in the drawings, namely the left side of the seat is plain and unornamented.

I claim:

The ornamental design for a vehicle seat, substantially as shown and described.
